UNITED STATES PATENT OFFICE.

GEORG GSCHWENDTNER, OF CINCINNATI, OHIO.

APPARATUS FOR ONE-BALL-BILLIARD GAMES.

SPECIFICATION forming part of Letters Patent No. 520,423, dated May 29, 1894.

Application filed December 26, 1893. Serial No. 494,663. (No model.)

To all whom it may concern:

Be it known that I, GEORG GSCHWENDTNER, a citizen of the United States, and a resident of Cincinnati, Hamilton county, State of Ohio, have invented a certain new and useful Apparatus for One-Ball-Billiard Games; and I do declare the following to be a full, clear, and exact description of the invention, such as will enable others skilled in the art to which it appertains to make and use the same, attention being called to the accompanying drawings, with the reference-numerals marked thereon, which form a part of this specification.

15 The subject of this invention is the apparatus required for playing a new species of the game of billiards. In this new game only one ball is used in conjunction with a rotary indicator and a numbered dial-plate against which the ball with more or less force is impelled, causing the indicator to revolve until it finally stops on a certain number which indicates the points made. I have therefore devised an apparatus for such purpose which is described and pointed out in the following specification and claims, together with its operation, parts, and construction, the latter being also illustrated in the accompanying drawings, in which—

20 Figure 1, is a perspective view of the apparatus in position for use. Fig. 2, is a top view, and Fig. 3, is a side-elevation, partly in section, of the same.

This game is played with one ball, preferably a billiard ball, in conjunction with the well-known cue used in connection with the game named. It should be played on a table which like a billiard table has a guard or raised edge around it, to prevent the ball 25 from rolling off. Inasmuch as all these parts are already in use and present in most billiard-rooms, they may conveniently be used and my apparatus forms then an adjunct thereto. Where these paraphernalia are not present, a table purposely constructed may be used. In such latter contingency it is however not required that this table should be of the same quality and elaborate construction as a billiard table and it is sufficient if it only furnishes the necessary protection to prevent the ball from rolling off.

The apparatus proper consists of a dial-plate 6, provided with a central standard 7, upon which the indicator 8 is supported. This latter is held in place by a bolt 9, passing through the central standard from below, and a thumb-nut 10 applied from above. By means of this latter the connection of the indicator may be regulated in a manner to cause it to revolve more or less freely. The dial-plate is divided into a number of fields, part of which are numbered. At one side the indicator projects beyond the dial-plate and is widened in a vertical direction as shown at 11, in order to provide a sufficient contact-surface against which the ball 12 may be impelled; the other end 13, is pointed and projects downwardly to within close proximity of the dial-plate. Inasmuch as part of this indicator on one side from the center is larger and heavier, it is expedient that the same should be counter-balanced by a weight 14, provided on the other side. This weight may be constituted by a fanciful ornament or figure as shown.

25 The game is played by shooting the ball against the projecting part 11 of the indicator whereby this latter is set to rotating. The position above which its pointed end comes to a stop indicates the result. If it stops between two numbered fields the shot may count as nothing, if over a numbered field it would count correspondingly with the number therein. These latter may represent values of any kind as may be agreed upon by the players. After each shot the indicator is returned again to its normal position as shown in Fig. 1, and which position is pointed out by two marks 15. It will be observed that the numbers are not arranged in sequence but follow indiscriminately each other. This brings variety into the game and also affords a chance to calculate the proper force or impetus the ball requires, to hit the indicator with more or less forcible impact, to influence its rotation, that it may stop over a certain number, preferably one of the higher ones. A flange 16, is provided all around the dial-plate to prevent the ball from rolling over the latter and thereby interfering with the rotation of the indicator.

30 17 is a guard provided adjacent to the en-

larged end 11, of the indicator and it also prevents the ball from running onto the dial-plate when the latter, while speeding against the mark should miss it or recoil therefrom. 5 18, is the table and 19 the raised guard around it which prevents the ball from rolling off.

Where this apparatus is used in connection with a billiard-table, it must be removable to 10 permit the table to be cleared when any of the other species of the game are played. Inasmuch as it cannot be rigidly connected I rely on frictional contact to keep the apparatus in position. This contact is obtained and 15 respectively increased by preparing the under surface of the dial-plate in a manner to give it a certain degree of roughness. This may be done by covering this surface with a sheet 20, of rough material like woolen cloth or can- 20 vas for instance.

Having described my invention, I claim as new—

1. A game-apparatus for the purpose described, consisting of a dial-plate adapted to 25 be removably set upon a billiard table while the particular game is being played, an indicator pivotally secured above it and extend-

ing laterally beyond the same and over the billiard-table top so as to come within possible reach of a ball manipulated suitably upon 30 the table and a flange to divide the dial-plate from the surrounding table-top to prevent the ball from striking any other part of the indicator except that which extends above and laterally beyond the dial plate. 35

2. A game-apparatus for the purpose described, consisting of a dial-plate provided with numbers, an indicator pivotally secured thereto and capable of rotating with its pointed end above the numbers and having its other 40 end broadened and projecting beyond the dial-plate so as to be adapted to be struck by a ball, and the guard 17, raised above the surface of the dial-plate and so located thereon as to be adjacent to the projecting, broadened 45 end of the indicator when the latter is in its normal position.

In testimony whereof I affix my signature in presence of two witnesses.

GEORG GSCHWENDTNER.
